UNITED STATES PATENT OFFICE.

DAVID B. GARTON, OF BARRIE, ONTARIO, CANADA, ASSIGNOR OF ONE-HALF TO EDMUND C. EDMONDS, OF ALBANY, NEW YORK.

SNOW-PLOW.

SPECIFICATION forming part of Letters Patent No. 291,182, dated January 1, 1884.

Application filed August 24, 1883. (No model.)

To all whom it may concern:

Be it known that I, DAVID B. GARTON, a subject of the Queen of Great Britain, and a citizen of Canada, residing at Barrie, in the 5 Province of Ontario, Canada, have invented certain new and useful Improvements in Snow-Plows for Railways, of which the following is a specification.

My invention relates to that class of snow-plows which are carried by the locomotive and forward of the same, in which an inclined shovel having at its outer sides parting-blades, made with a mold-board form, and intermediate slicing or stripping blades, also made with 15 a mold-board form, co-operate together to separate and part the snow on the railway-track from the snow at the sides thereof, and also divide the snow on the track into slices or strips, to be carried upwardly, and throw the 20 same outward on the snow at one or both sides of the track, accordingly as the track to be cleared is a single or double track, and the plow is made to be a single-side or double-side clearing-plow.

25 The objects of my invention are to provide means by which the snow on the track will be separated from the snow at the sides thereof, and be cut into strips, and the strips of snow thus formed be elevated and thrown outward 30 on the snow, with the portions of the snow taken from the more central portions of the track elevated the highest and finally thrown outward without any wedging or packing of the snow, as heretofore. I attain these objects 35 by means of the mechanism illustrated in the accompanying drawings, in which there are seven (7) figures illustrating my invention, in all of which the same designation of parts by letter-reference are used.

40 Referring to the drawings, Figure 1 is a side elevation of my improved snow-plow. Fig. 2 is a horizontal view, from above, illustrating a single-track plow. Fig. 3 is a front end view. Fig. 4 is a rear end view. Fig. 5 is a 45 horizontal view, from above, of a double-track plow. Fig. 6 is a front end view, and Fig. 7 is a rear end view.

In the drawings, A represents the shoe of the plow, which shoe is made, preferably, of 50 stiff plate metal—such as boiler plate-iron or

plate-steel—and with a width a little greater than that of the track from which the snow is to be cleared. In plows intended to clear snow from a railway having a single track, I make the shovel portion of the same to incline in 55 one direction, upward and rearward, as shown in Fig. 1, and with its two halves or side portions, a a, to incline in opposite directions from a line through its middle of width downward and outward to the sides thereof, as 60 shown in Figs. 2, 3, and 4. These inclined sides of the shovel portion of the plow are also made of stiff plate iron or steel. Securely bolted or riveted to the said inclined half portions of the shovel, at their outer edges, are 65 the parting-blades B B, which blades are also made of stiff plate iron or steel. The forward and lower ends of these parting-blades are preferably made to incline slightly outward, as shown in Fig. 3, though they may be made 70 to be substantially vertical. Said parting-blades have a vertical extension of about from fifteen to twenty inches, more or less, as may be deemed sufficient to cut through that or a less or greater depth of snow. These blades 75 are made to run upwardly and rearwardly, with a gradual outward curving of the same until they lie at their rear ends about horizontal, as shown in Figs. 2, 3, and 4, and project over the side edges of the shovel to a distance about or nearly equal to their width.

Securely bolted or riveted to the inclined side portions, a a, of the shovel, and intermediate between the parting-blades B B, are a series of slicing or stripping blades, C C, which 85 also are made of plate metal. These stripping or slicing blades are made with a vertical extension of width about equal to that of the parting-blades B B, and also are made to have a mold-board form, by being each gradually 90 curved over the next lower neighboring blade, as shown. The channel formed between each of two neighboring blades, as between blades B and C, or blades C and C, operate to conduct the snow in strips, each in a separated 95 manner, from the snow at the sides of the track and from each of the other strips, and deliver the same at the sides of the plow on the snow at the sides of the track.

In a double-track snow-plow I make the 100

shovel portion *a* of the shoe inclined upwardly and rearwardly, as shown in Fig. 1, and also make it to incline from one of its side edges upwardly and laterally to the opposite side, as shown by dotted and full lines in Figs. 5, 6, and 7. By this manner of inclination of the entire shovel-portion of the plow, the snow worked up on the off side surface of the shovel will be more elevated than that worked up on the high side, or the side the entire body of the track-snow is to be delivered. Securely bolted to the low side edge and to the elevated side edge of this shovel, by bolts or rivets, are the parting-blades *B B*, which parting-blades are made of stiff plate metal, and with a width or vertical extension (in front) of about fifteen to twenty inches, more or less. The parting-blade *B* on the lower side edge of the shovel is made to gradually turn or curve outward with a mold-board form as it runs rearward. The parting-blade at the opposite side edge, or higher edge, is made to turn or curve in the same direction, or toward the lower side parting-blade, as shown in Figs. 5, 6, and 7.

25 Securely attached to the inclined shovel, by bolts or rivets, are the intermediate slicing or stripping blades, *C*, which are each made with about the same width as the parting-blades, and are in like manner gradually turned or 30 curved over toward the lower side edge of the shovel, with a mold-board form substantially the same as the parting-blades, so that all the blades, both the parting and intermediate slicing-blades, will have their mold-board portions, turn or curve in direction of the lower side edge of the inclined shovel.

With this form of construction and arrangement of parts in the modification shown in Figs. 5, 6, and 7, the snow on the track will 40 be parted from the snow at the sides of the track, and will be gradually elevated as the plow is carried forward by the locomotive, and be cut into strips, which strips will have an upward passage through the channels from 45 between each two neighboring blades, and the snow will be delivered in its entire body at one side of the track.

This double-track plow may be made to throw the snow to the right-hand side or the 50 left-hand side, so that on a double-track railway the snow may be thrown out and off the two neighboring tracks on the off side of the same.

In the operation of my improved snow-

plow, whether it be a single or double track 55 plow, the packing and wedging together of the snow on the track with that on the sides thereof, as heretofore, is wholly avoided, and the locomotive will be enabled to run with a speed of from twelve to twenty miles per hour, 60 and clear the track of snow in a rapid and comparatively easy manner, and without making stoppages, as heretofore required.

Having described my invention, what I claim, and desire to secure by Letters Patent, is— 65

1. In snow-plows for railways, the combination, with the angular or inclined sides of shoe *A*, of the oppositely-located and vertically-arranged parting-blades *B B*, which have each their upper marginal portions inclined and made to curve outwardly with a gradually-increasing extension of lateral projection of said margin portions as they are made to run upwardly and rearwardly, substantially as and for the purpose set forth. 70

2. In snow-plows for railways, the combination, with the oppositely-inclined sides *a a* of shoe *A*, and the vertically-arranged parting-blades *B B* situated at the outer sides of said shoe, and made to have their upper marginal edge portions extended outwardly with a gradually-increasing curve as they run rearwardly and upwardly, of a series of one or more intermediate and vertically-arranged slicing-blades, which have a gradually-increasing vertical extension above blades *B B*, and outwardly-curved and laterally-projecting marginal portions, which gradually increase in the outward throw of curve as said curved portions run upwardly and rearwardly, substantially as and for the purpose set forth. 80

3. In a snow-plow for railways, the combination, with shoe *A*, having oppositely-inclined sides, of the vertically-arranged outer 95 side parting-blades, *B B*, and the series of vertically-arranged slicing-blades situated intermediate between said parting-blades, and having a gradually-increasing vertical extension above the said parting-blades as they run rearwardly and upwardly, all substantially as and for the purpose set forth. 100
